R. BUTLER

TOBACCO PIPE

Filed April 28, 1925

INVENTOR=

Robert Butler

MacLeod, Culver, Copeland & Dick

ATTORNEY^E

UNITED STATES PATENT OFFICE.

ROBERT BUTLER, OF BOSTON, MASSACHUSETTS.

TOBACCO PIPE.

Application filed April 28, 1925. Serial No. 26,508.

To all whom it may concern:

Be it known that I, ROBERT BUTLER, a citizen of the United States, residing at Boston, county of Suffolk, State of Massachusetts, have invented a certain new and useful Improvement in Tobacco Pipes, of which the following is a specification, reference being had therein to the accompanying drawings.

- 10 The invention relates to a new and useful improvement in tobacco pipes. The object of the invention to provide a tobacco pipe in which the tobacco will burn down evenly in the bowl, the clogging of the smoke passages will be lessened, and outside air will be drawn in to mix with the smoke to condense vapors from the burning tobacco thereby lessening the entrance of the same into the mouth of the smoker. One feature of the 15 invention consists in providing a mouthpiece having in addition to the smoke passage therein a passage into which a tube is inserted to communicate with the outside air. Another feature consists in providing 20 a condensing chamber having an air-cooled tube passing within the chamber and thereby forming a condensing member thereof. Another feature consists in providing a tubular member placed in the stem portion of 25 the pipe so that one end thereof shall communicate with the fire chamber in the bowl, and the other end with the outside air through a passage in the mouthpiece, said tube passing within and through said condensing chamber and communicating therewith through a port that divides said tube 30 into a smoke passage and an air passage, said air-cooled portion of said tube thereby forming the internal condensing member of 35 the said condensing chamber. Other features of the invention will be set forth hereinafter.

The invention will be fully understood from the following description when taken 40 in connection with the accompanying drawings and the novel features thereof will be pointed out and clearly defined in the claims at the close of this specification.

In the drawings:

- 50 Fig. 1 is a longitudinal section of a pipe embodying the invention.
- Fig. 2 is a section on line 2—2, Fig. 1.
- Fig. 3 is a detail view, in side elevation, of the tubular member.
- 55 Fig. 4 is a bottom plan of the tube, Fig. 3. Referring now to the drawings:

1 represents the bowl, 2 the stem of the bowl, and 3 the mouthpiece. The stem 2 and the mouthpiece 3 are connected together by a shell-like rim, band or sleeve 4 in such manner as to enclose a condensing chamber 5. This member 4 will, for brevity, be hereinafter referred to as a shell. 2, 3 and 4 outline the stem of the pipe. 6 is a passage in the stem of the bowl and 7 a passage in the mouthpiece into which the tube 8 is fitted. 9 is a fire chamber in the bowl, 10 and 11 are ports in the tube 8, 12 the smoke passage in the mouthpiece, and 13 an air port for passage 7 or for tube 8.

Preferably the shell-like member 4 is of thin metal but may be of any other suitable material, and preferably it is separable from the stem 2 but may be fastened to or be a part thereof.

Preferably the mouthpiece 3 fits into and is separable from the shell 4 but may be fastened to or form said sleeve.

Preferably the tube 8 is of thin metal but may be of any other suitable material, and preferably it is separable from the stem 2 and the mouthpiece 3 but may be fastened to or be a part of either. When assembled, tube 8 extends across the lower portion or bottom of the fire chamber 9, through the passage 6 of the stem 2, within and through the condensing chamber 5, and into or through the passage 7 of the mouthpiece 3. Tube 8 communicates with the outside air through the port 13, with the condensing chamber 5 through the port 11, and with the fire chamber 9 through the port 10.

Port 10 is preferably placed on the under side of the tube 8 to allow the drip to clear from the tube and to prevent the clogging of the port by the tobacco from above. Port 10 is extended well into the wall of the tube 8 so that suction action will be distributed over the bottom of the fire chamber 9 thereby causing the smoke to spread and divide to enter the tube and thereby causing the tobacco to burn down evenly in the bowl of the pipe.

Port 11 divides the tube 8 into a smoke passage and an air passage and determines their relative lengths. Port 11 is preferably placed on the under side of the tube 8 to allow the drip to clear from the tube and to fall into the condensing chamber 5. Port 11 is preferably located near the stem 2 of the bowl so as to extend the cold-air portion of the tube 8 as far into the condensing

chamber 5 as may be possible thereby forming an internal condensing member for said condensing chamber. It is because of port 11 that air and smoke are forced to come together within the tube 8 and mix before passing from the tube.

When the pipe is in action, smoke is drawn into the tube 8 through the port 10 and air is drawn into said tube through the port 13 and the smoke and air come together within the tube. The mixture then passes through the port 11 and enters the condensing chamber 5, thence through said condensing chamber and the passage 12 in the mouthpiece to enter the mouth of the smoker.

The condensing chamber 5 is cooled externally through the thin-walled sleeve 4 that encloses said chamber and is cooled internally by the air-cooled portion of the tube 8 that extends within said chamber and forms a condensing member thereof and also by the air that enters said chamber through said port 11 of said tube 8. Said condensing chamber 5 serves to condense vapors from the burning tobacco and to collect and to hold the same thereby lessening their entrance into the mouth of the smoker. Said condensing chamber 5 serves also to cool the smoke and to minimize the heating of the mouthpiece of the pipe.

The entire device is simple of construction, being of few parts, easily assembled and easily separated for cleaning. Preferably the mouthpiece 3, the shell 4, the tube 8 and the stem 2 of the bowl of the pipe are separable each from the other by sliding contacts fitted to prevent leakage.

What I claim is:

1. A tobacco pipe having a condensing chamber, a mouthpiece having an inlet passage leading from the outside air to said chamber, a tube extending across the lower portion of the fire chamber of the bowl, thence through the condensing chamber and into said inlet air passage in the mouthpiece to communicate with the outside air, said tube having a port communicating with the fire chamber at or near the bottom of said fire chamber and so constructed and located that the smoke shall divide to enter the tube, said tube having intermediate its ends a port which communicates with said condensing chamber, the portion

of the tube on one side of said last mentioned port constituting an air passage and the portion of the tube on the other side of said port constituting a smoke passage.

2. A tobacco pipe having a condensing chamber through which the smoke and outside air must pass on their way to the mouthpiece, said condensing chamber being located in the stem portion of the pipe and inclosed by an air-cooled shell, a tube which passes through said condensing chamber and communicates at one end with the fire chamber of the pipe and at the other end with the outside air through a passage in the mouthpiece, said tube also communicating with said condensing chamber through a port that divides the tube into a smoke passage and an air passage, said last named port being so located that the air passage portion of said tube shall extend some distance into said condensing chamber and form an internal condensing member.

3. A tobacco pipe having a mouthpiece connected with the stem of the bowl by a shell that encloses a condensing chamber through which the smoke and outside air must pass on their way to the smoke passage of the mouthpiece, said mouthpiece being formed with a passage into which a tube is fitted to communicate with the outside air, said tube extending within said condensing chamber and communicating with it, said passage of the mouthpiece into which said tube is fitted communicating with the smoke passage of the mouthpiece through said tube and said condensing chamber.

4. A tobacco pipe having a condensing chamber located in the stem portion of the pipe and inclosed by an air-cooled shell, a tube communicating at one end with the fire chamber of the bowl and passing through said condensing chamber and connecting with a passage in the mouthpiece communicating with the outside air, said tube having a port which communicates with said condensing chamber and divides the tube into a smoke passage and an air passage.

In testimony whereof I affix my signature.

ROBERT BUTLER.
